UNITED STATES PATENT OFFICE

2,422,537

MACHINE FOR COATING INSULATORS

Eugene H. Fischer, Derry, Pa., assignor to Westinghouse Electric Corporation, East Pittsburgh, Pa., a corporation of Pennsylvania

Original application July 31, 1940, Serial No. 348,804. Divided and this application September 28, 1943, Serial No. 504,126

3 Claims.

(Cl. 91—46)

1

The present invention relates to the coating of ceramic bodies and it has particular relation to the application to electrical insulating bodies of coatings which are to cover only a predetermined portion thereof.

This is a division of my application filed July 31, 1940, Serial No. 348,804, now Patent 2,333,557 which issued November 2, 1943.

In the electrical insulator art, it has become common practice to apply a conducting coating to portions of insulators, generally in addition to the regular glaze, for such purposes as the suppression of radio interference. This conducting coating is applied to the insulator surface at and adjacent to the points of contact with conductors and other metallic parts or members to reduce electrical discharge to the insulator surface. The coating material employed is preferably a liquid of the composition described in Hunt U. S. Patent No. 1,973,076, while further consideration of the principles involved may be found in Patents No. 1,987,683 and No. 1,997,688.

Insulators of the pin-type, for example, are generally provided with a coating of this type at the upper surface to cover the conductor and tie-wire groove portions and also within the pin hole. For each type and size of insulator, the most efficient and effective extent of the conducting coating is readily determinable. Since application of the coating to any greater amount of the surface results in a waste of material and may impair the effectiveness of the insulator, the industry has encountered the problem of accurately and uniformly applying this material to the proper surface portion of the insulator in an inexpensive and efficient manner.

According to one embodiment of the present invention, an intermittently driven conveyor is provided to carry insulators placed thereon in sequence to a predetermined stationary position serving as an operating station. A multi-armed member which is intermittently rotated in synchronism with the conveyor moves downwardly as each insulator reaches this predetermined position and grips it to remove it from the conveyor. At the same time another arm of the conveyor dips an insulator previously picked up by it to a predetermined depth in coating liquid disposed in a constant level receptacle disposed elsewhere along the periphery of the rotating member. Thus, the device continuously coats the desired area of the insulators at a rapid rate and it is only necessary for an operator to place the articles on the conveyor at some point in its travel and remove them from the rotating member after completion of the coating process. It will appear evident that the invention is not limited to any particular type of insulator and may be used to coat articles with

2

materials other than the conducting or semi-conducting compound previously described.

It is accordingly an object of the present invention to provide an improved means for applying a coating to ceramic bodies.

It is another object of the invention to provide improved apparatus for coating a predetermined portion of the surface of electrical insulators.

Other objects and advantages of the invention will appear from the following detailed description taken in conjunction with the accompanying drawings in which:

Figure 1 is an enlarged view in vertical section of a type of insulator treated in accordance with the present invention;

Fig. 2 is a fragmentary end view in vertical section of the mechanism of the invention;

Fig. 3 is a side view of the structure shown in Fig. 2;

Figs. 4 and 4A are fragmentary views of control devices used in the operation of the invention;

Fig. 5 is an enlarged view in vertical section of a work-holder involved in such operation; and

Fig. 6 is an exploded perspective view of the driver of the apparatus.

The figures of the accompanying drawing correspond to Figs. 3, 6, 4, 5, 13, 11 and 12, respectively, of said Patent 2,333,557 of which this application is a division, and the same reference characters are used in both cases.

In the drawings is shown apparatus for treating an insulator such as is shown in Fig. 1 in accordance with the invention. The embodiment illustrated is such as will coat the insulator with glaze over a predetermined area of the outer top surface as at b.

Referring now to the drawing, the apparatus includes a conveyor comprising a plurality of cars or trays 2 (Fig. 3) which are pivotally connected to each other by means of roller pins 4 to form an endless chain. For a detailed description of the construction of the conveyor, reference may be had to the aforesaid Patent 2,333,557. The conveyor moves intermittently, as described in such patent.

Located near the driving end of the conveyor is a dipping assembly 58 (Fig. 3) which includes a plurality of angularly spaced arms 60 attached to an index head 62 which is, in turn, supported from a vertical column indicated at 64. The index head is adapted to operate in synchronism with the conveyor and on the end of each of the arms is disposed a chuck 66 for gripping an insulator when it is disposed at a particular position of the conveyor. Having particular reference to Figs. 4, 5 and 6, the driving sprocket 14 is arranged to be driven from a motor 68 through an intermittent drive including a driving disk 70 and a Geneva gear 72. The driving disk 70 is

keyed to a driving shaft 74 which is driven by the motor and includes a driver pin 76 for engagement between the spokes of the Geneva gear to intermittently drive a shaft 78 to which it is attached. With a Geneva gear having 5 spokes, as shown, it will be evident that its shaft will be rotated through $\frac{1}{5}$ of a revolution for each revolution of the driving disk. Likewise, the sprocket 14, which is fixed to the shaft 78 will be driven $\frac{1}{5}$ of a revolution during the same time. Since the rollers 4 between the trays are adapted for engagement by spokes 80 of the driving sprocket, each of them will be driven a predetermined distance during the motion of the sprocket to bring each of them, in turn to a predetermined stationary position.

Attached to one side of the driving disk 70 is a cam shoe 32 while a cam pin 84 extends further out from the leading edge of this cam shoe. The cam shoe and cam pin are disposed to engage the cam followers 42 and 44, respectively to actuate the push rods 38 and 40 in synchronism with the movement of the conveyor.

As is best shown in Fig. 2, the vertical column 64 for the dipping mechanism is secured at its bottom to a metal flange 86 which is in turn attached by any suitable means to a base member 88. Disposed within the lower end of this column is a metallic base member 90 having a recess 92 within which is seated the lower end of a cylindrical body 94. A cylinder bonnet 96 having an opening 98 through which a main vertical shaft 100 extends is disposed on the upper end of the cylinder while suitable packing means 102 surrounds the shaft at this point. A piston member 104 is secured to the lower end of the shaft 100 to fit snugly within the cylinder while an air-pressure pipe 106 communicates with the bottom of the cylinder at a point below the lowermost travel of the piston. The index head 62 is secured to the shaft 100 in a vertically adjustable position between nuts 107 engaging the screw threaded upper end thereof.

Located within the upper end of the vertical column 64 is a top bearing support 108 which carries a bushing 110 for engaging the shaft 100. A central bearing support 112 is disposed in the vertical column intermediate the ends and also includes a bushing 114 for engaging the shaft 100. A bevel gear 116 is attached to the shaft 100 at a point above the central bearing support by means of a key 118. This key fits into a longitudinal slot 120 in the shaft 100 so that the shaft itself may be moved vertically upward while the gear 116 remains stationary. The gear is held in the stationary position by means of a bearing spacer 122 which engages the top bearing support at its upper end and is secured at its lower end to a collar member 124. This collar member 124 engages the gear 116 through a bearing 126.

It will be seen that this gear 116 is engaged by another bevel gear 128 which is secured to a shaft 129. As described in the aforesaid patent, the shaft 129 is driven from the shaft 78 of the conveyor which carries the Geneva gear 72 (Fig. 3 hereof). In addition, a sprocket wheel 130 is secured to the driving shaft 74 and engaged by a chain 132 to drive another sprocket member 134. The sprocket 134 is keyed to a shaft 136 which has a cam 138 (Fig. 4 hereof) at its other end for operating a valve 140 for controlling the admission of air to the pipe 106 to raise and lower the shaft 100.

Referring to Figs. 2 and 5, it will be seen that the spindle head 62 includes an annular passage

266 which communicates with the interior of the arms 60 as well as with tubular members 268 which lead to a vacuum pump or tank, as indicated. On the end of each of the arms, there is disposed a tubular casing 270 which is secured thereto by means of bolts 272 while an apertured baffle member 274 extends therebetween. A cap portion 276 is fitted over the top of the casing in sealed relationship while a bushing 278 is centrally arranged within it. Within the bushing is located a tubular shaft 280 which is slidably arranged within the casing and includes an axial opening 282 communicating with a radial opening 284. The radial opening is arranged to communicate with the interior of the arm 60 through apertures in the casing and bushing when the shaft 280 is in an upward vertical position.

To the lower end of the shaft 280 there is secured a horizontal plate 286 to which is cemented a soft rubber pad 288. An aperture is provided in the pad 288 to permit communication of vacuum with the interior of the insulator 1 engaged thereby. A compression spring 290 is disposed around the shaft 280 between the member 286 and a bottom member 292 attached to the casing 270. In addition, collars 294 and 296 are secured to the shaft 280 to limit respectively the downward and upward motion thereof.

A bracket member 298 is secured to the casing, as indicated, in order to pivotally support an operating lever 300. A spring 302 is disposed between the casing and the operating lever to bias the lower portion of the lever including prong 304 inwardly. The prong 304 is adapted to engage either the lower surface of a flange 306 or the member 286 or one of the annular grooves 308 therein.

Thus when the chuck is moved downwardly so that the rubber pad 288 engages an insulator such as that indicated at 1, the tubular shaft is pushed upward in the casing to bring the opening 284 into communication with the vacuum source. At the same time, the operating lever, being biased inwardly, grips the flange 306 or one of the grooves 308 therein to lock the shaft 280 in communication with the vacuum source after the chuck unit is moved upwardly and thus hold the insulator thereon. To release the article, it is only necessary to push inwardly on a knob 310 on the operating lever to permit the spring 290 to force the shaft 280 out of communication with the vacuum source.

At a predetermined position along the path of rotation of the arm 60 is, disposed a receptacle 312 for glazing fluid. This receptacle is provided with annular overflow chamber indicated at 314 from which fluid may be removed by means of a tube 316 to maintain constant the level in the receptacle. At the same time, the interior passage of a tubular supporting member 320 communicates with the interior of the receptacle 312 to permit the pumping of additional fluid into it from the bottom. In order to prevent undue agitation of the fluid, a baffle plate 322 is disposed over this lower entrance. The support 320 is screw threaded and secured within a bracket 324 attached to the stationary part of the apparatus so that the vertical position of the receptacle may readily be adjusted.

The control of the valve 140 for causing vertical movement of the shaft 100 and index head 62 will be readily understood upon reference to Fig. 4. The four-way valve 140 may be of usual construction and in addition to communicating with the pipe 106 which leads to the air cylinder

94 has another passage connected with a compressed air source through a pipe 326. The remaining passages are closed by a plug 328 and open to the atmosphere, respectively. An operating link assembly for the valve is pivoted about a fixed point 330 and connected to a spring 332 to bias a pin 334 thereon against the surface of the cam. In the embodiment shown the pipe 106 is open to the atmosphere when the pin 334 engages the lower cam surface and is connected to the air pressure pipe 326 when the pin bears against the raised surface of the cam.

In operation, the dipping mechanism is in its downward position as shown in Figs. 2 and 3 so that an insulator on one of the chucks 66 is being dipped to a predetermined depth in the receptacle 312. Under the control of cam 138 (Fig. 4), the raised portion thereof engages the pin 334 causing the valve 140 to permit the passage of compressed air into the bottom of the cylinder 94 to raise the index head 62 of the dipping mechanism upwardly and withdraw the insulator from the receptacle 312. At the same time another chuck 66 lifts from the conveyor an insulator which it engaged while the index head 62 was lowered to its down position.

As described in the aforesaid patent, the conveyor then advances one step and during such movement the now elevated index head rotates one step to bring another chuck 66 to a position directly above another insulator on the conveyor; moves the just lifted insulator into dipping position; and moves the dipped insulator away from the dip-tank.

While the driving pin 76 is out of engagement with the Geneva gear the lower portion of the cam 138 engages the pin 334 causing the valve 140 to connect the pipe 106 to the atmosphere. The index head 62 then drops to its lower position in which the chuck positioned directly over the insulator on the conveyor engages it and the insulator gripped by the chuck directly over the receptacle 312 is dipped therein.

It will appear evident that the apparatus may be readily adapted to handle articles of various different sizes. The position of the index head 62 on the movable shaft 100 may be adjusted by means of the nuts 107 while the vertical position of the glaze tank may be changed through the medium of the bracket support 324. Different sized adapters may be used in the holder units and, if desired the size of the holders themselves may be changed. The chuck units 66 readily accommodate themselves to slight variations in insulators of the same general size because of the grooves 308 thereon. The speed of operation is controllable in a simple manner while the various cams may be designed to provide the most desirable operating cycles.

While only one of the holes 142 in each tray is shown provided with insulator holders and only a single dipping mechanism 58 is employed, it will be evident that this and the pin coating mechanism may be duplicated to simultaneously treat two rows of insulators. It is also within the scope of the invention that electrical timing and solenoid equipment may be substituted for the mechanical cam arrangements shown to properly control the cycle of operation.

Since these and numerous other modifications may be made without departing from the spirit and scope thereof it is intended that the invention be limited only by the appended claims interpreted in view of the prior art.

I claim as my invention:

1. Coating apparatus comprising a rotatable member, a support therefor, a plurality of angularly displaced means on said member for holding articles to be coated, means for intermittently rotating said rotatable member to successively bring each of said holding means to each of a pair of predetermined stationary positions with one of said holding means at each of said positions at each stop, means for moving an article to a position under a holding means at the first said predetermined position, a receptacle for holding liquid coating material to a predetermined depth under a holding means at the second said predetermined position, means for automatically lowering said rotatable member a predetermined amount while in each of its stationary positions to cause the holding means in said first predetermined position to contact and grip an article and the holding means in said second position to dip an article thereon to a predetermined depth in said receptacle.
2. Coating apparatus comprising a rotatable member and a support therefor, a plurality of equally spaced arms disposed radially from said rotatable member, a holding member on the under side of each of said arms, said holding member being capable of gripping a ceramic article upon being brought into contact therewith, means for intermittently rotating said rotatable member to successively bring each of said arms to each of a pair of predetermined stationary positions spaced apart by a multiple of said arm spacings, a receptacle located at said second predetermined position for holding liquid coating material to a predetermined depth, means for automatically lowering said rotatable member and arms a predetermined amount with arms in said predetermined positions to cause the holding means on the arm in said first position to contact and grip a ceramic article thereat and to dip a ceramic article on the arm in said second position to a predetermined depth in the material in said receptacle.
3. Coating apparatus comprising a substantially horizontal rotatable member, a plurality of article holders mounted in an annular series on said member, said article holders being designed to grip an article upon engagement therewith, means for intermittently rotating said member to bring each of said holders in sequence to each of a pair of angularly displaced predetermined positions, means for supporting an article to be coated at the first of said predetermined positions, a receptacle for holding liquid coating material at the second of said predetermined positions, and means for relatively moving said rotatable member and said supporting means while a holder is in said first position to cause it to grip an object thereon and for relatively moving said rotatable member and said receptacle while a holder is in said second position to dip an article thereon to a predetermined depth in said receptacle.

EUGENE H. FISCHER.
